HEEL ATTACHING MACHINE

Thomas Baggott Clarke, Leicester, England, assignor to United Shoe Machinery Corporation, Flemington, N. J., a corporation of New Jersey

Application September 2, 1948, Serial No. 47,459
In Great Britain September 24, 1947

5 Claims. (Cl. 1—32)

1

This invention relates to heel attaching machines and is illustrated herein as embodied in a machine of the general type disclosed in United States Letters Patent No. 2,391,543, granted December 25, 1945, upon an application filed in the name of Joseph W. Carr, et al., provided with an improved heel holder.

The present invention which is fully disclosed in the following description and claims consists in the novel features hereinafter described, reference being had to the accompanying drawings which show one embodiment of the invention selected for the purpose of illustration.

In the drawings,

Fig. 1 is a front view of a portion of an operating head of the machine disclosed in said Letters Patent No. 2,391,543 provided with an improved heel holder;

Fig. 2 is a plan view on line II—II of Fig. 1 showing in heel attaching position the heel holder of the illustrative machine;

Fig. 2a is a section on line IIa—IIa of Fig. 2;

Fig. 3 shows in front elevation manually actuated portions of mechanism for operating centering fingers and clamps of the heel holder;

Fig. 4 is a vertical section on line IV—IV of Fig. 1 showing mechanism for automatically swinging the fingers of the heel holder away from a heel positioned in said holder preparatory to raising the heel holder to force said heel with final heel attaching pressure against the heel seat of a shoe which is mounted upon a shoe support and into which nails have been driven and beyond which the nails project;

Fig. 5 is a view on line V—V of Fig. 4; and Fig. 6 is a section on line VI—VI of Fig. 5.

The illustrative machine is shown and described as embodied in the heel attaching machine disclosed in said Letters Patent 2,391,543 and comprises a support or holder 20 (Fig. 1) for a shoe 21 mounted upon a last 23 and nail supplying mechanism 22 which are mounted upon the upper part of a main frame 24 (Figs. 1, 2 and 4) of the machine, and a heel support or holder 26 and nail driving mechanism 28 which are secured by screws 30, 32 (Fig. 1) respectively to a carriage 34 movable on wheels 36 along a track 38 secured to and forming part of the main frame of the machine. A heel 40 (Figs. 1 and 2) which has been pricked by awls in a suitable pricking machine (not shown) is positioned upon the heel support 26 when said support is in a heel receiving position in which it is shown in dash lines on Fig. 1, away from a heel attaching position in which it is shown in full

2

lines. In placing the pricked heel 40 upon the heel support 26, which corresponds to the heel support best shown in Fig. 3 of said Letters Patent 2,391,543, the breast of the heel is placed against a breast gage or abutment 42 and inner and outer pairs of levers, fingers or clamps 44, 46 (Figs. 1, 2 and 5) then held in their open positions away from the heel are released by mechanism which will be hereinafter described, to center the heel upon the heel support 26 and to hold the breast of the heel against said heel breast gage 42.

When the heel support 26 is in its heel receiving position in which it is shown in dash lines (Fig. 1) passages 48 of a nailing die or block 49, which passages have previously received a load of nails 50 from a foot plate 52 of the nail supplying mechanism 22 and have a pattern similar to that of awl holes 54 pricked in the attaching face of the heel, are positioned beneath the shoe support 20. When a one-revolution clutch (not shown) is tripped in response to depression of a treadle (not shown), the machine operates through a cycle causing the shoe support 20 to be lowered to force a fitted heel seat 56 of the shoe which is positioned upon and secured to the support 20, against the upper surface 58 of the nailing die 49. The shoe is thus held against the nailing die 49 while a piston 60 slidably in a cylinder 62 of the nail driving mechanism 28 is forced upward by a plunger 64 (Figs. 1 and 4) to operate a plurality of drivers 66 which fit slidably in the passages 48 of the nailing die 49 and drive the nails then in said passages part way into the heel seat 56 of the shoe. The nails 50, which are partly driven into the heel seat 56 of the shoe 21 mounted upon the support 20 by the drivers, are left projecting from the heel seat of the shoe as shown in Fig. 1 and are arranged in the same design as the awl holes 54 in the attaching face of the heel 40, the heel upon the holder 26 and the shoe upon the support 20 being moved toward each other during a second cycle of operation of the machine to cause the heel to be forced against the heel seat of the shoe with the nails forced into the respective awl holes of the heel.

During the last part of the first cycle of operation of the machine the shoe support 20, together with the shoe 21 which is clamped to said support and into the heel seat 56 of which the nails 50 have been partially driven, is moved to the raised position shown in Fig. 1, in which position it comes to rest spaced a considerable distance from the nailing die 49. After placing

the pricked heel 40 upon the support or holder 26, the carriage 34, to which the heel holder and the nailing die 49 are secured, is moved to the right, as viewed in Fig. 1, against a stop 68 on the main frame 24, by the use of mechanism such as disclosed in detail in said Letters Patent No. 2,391,543, operated by a crank 70, to its position shown in Fig. 1, the heel holder then being positioned beneath the shoe support 20 and the nailing die 49 being positioned beneath the foot plate 52 of the nail supplying mechanism 22. When the heel 40 is thus positioned the awl holes 54 in the attaching face of the heel are in alignment with corresponding nails 50 projecting from the heel seat 56 of the shoe 21 mounted upon the shoe support 20, the construction and arrangement being such that when the shoe is moved downward with the support the nails enter the awl holes in the heel.

The heel support 26 comprises a two-part table 72 (Figs. 1, 2, 2a, 4 and 5) having an upper surface 74 (Figs. 2 and 5) on which the heel 40 is positioned attaching face up, the breast of the heel being in engagement with the breast gage or abutment 42 which is mounted upon a pivot pin 76 (Fig. 2) secured to the table 72. Secured to a sleeve 78 (Figs. 2 and 2a), rotatably mounted in the table 72, and formed integral with a stud 80 coaxially arranged with the sleeve and rotatable in a bore 82 (Fig. 2a) of the sleeve are 30 the outer and inner pairs of levers or fingers 46, 44 which have, rotatably mounted in their forward ends, rolls 84, 86 (Fig. 2) constructed and arranged to be forced by mechanism hereinafter described against opposite sides of the heel to center said heel and to hold it in place against the breast gage 42. Formed integral with the sleeve 78 and the studs 80 are equalizer arms 88, 90 respectively (Figs. 2, 2a and 5) which are geared for equal and opposite movement, the fingers 44 and 46 being constantly urged toward their closed positions by springs 82, 94 (Fig. 2) forward ends of which are fixed to studs carried by the table and rear ends of which are attached to the outer ends of extensions of said arms. When there is no heel in the machine inward movement of the inner arms 44 under the action of the spring 94 is limited by mechanism which is hereinafter described and comprises a stop screw 96 (Figs. 2 and 4), inward movement of the outer arms 46 acted upon by the spring 92 being limited by the engagement of the right-hand arm 46 as viewed in Fig. 2 with a depending stop lug 98 (Fig. 2) on the right inner arm 44.

The right equalizer arm 90 as viewed in Fig. 2 has pivotally connected to it a link 100 a forward end of which is pivotally connected to the right end of a lever 104 (Figs. 1 and 2) fulcrumed on a pivot pin 106 (Fig. 2) secured to the table 72. Pivot upon a pin 108 (Figs. 2 and 3) carried by the lever 104 and sliding in a bifurcated portion of said lever is a hand knob or latch 110 (Figs. 1, 2 and 3) which is constantly urged clockwise as viewed in Fig. 3 by a spring 112 housed in a recess 114 of the lever and engaging the knob. Pivotally connected to the knob 110 is a latching pin 116 (Figs. 2 and 3) which slides in a bore 118 of an upstanding lug of the lever 104, an end of the pin being normally forced against an edge 120 of the table by the spring 112. When the knob 110 is thus positioned the lever 104 is moved clockwise as viewed in Fig. 2 until the fingers 44, 46 engage the heel, or in the event that there is no heel in the machine, until the stop screw 96 engages the head of a rod 152 75

hereinafter described. When it is desirable manually to open the fingers 44, 46 the knob 110 is drawn forward and released, rearward movement of the lever 104 and accordingly the closing of said fingers actuated by the springs 92, 94 being prevented by engagement of the pin 116 with a shoulder 122 (Fig. 2) on the table.

The heel holder 26 comprises a platform 124 (Figs. 1, 2, 4 and 5) which has a depending plunger 126 slidably fitting in a vertical guideway 128 (Figs. 1, 4 and 6) of a pedestal 130 of the holder and which has in its upper face an undercut groove 132 in which fits a complementary depending portion 134 (Figs. 4 and 5) of the table 72, said table being held against movement lengthwise of the groove by a pin 136 (Figs. 2 and 5) which is carried by the platform 124 and the inner end of which fits in a recess 138 in the depending portion 134 of said table. The pin 136 may be manually removed from the recess 138 of the table 72 preparatory to changing tables when it is desired to operate upon another type of work. In a machine such as disclosed in United States Letters Patent No. 2,480,905, granted September 6, 1949, on an application filed in the name of Thomas B. Clarke et al., which machine has a pricking unit, a pin (not shown) corresponding to the pin 136 may be automatically withdrawn from a depending portion of the table when the heel holder arrives at a pricking station preparatory to automatically moving the table forward to facilitate placing the heel to be operated upon in the machine.

Threaded into the lower end of the depending plunger 126 of the platform 124 is a screw 140 (Figs. 1 and 4) having a head 142 which normally engages an inturned flange 144 at the lower end of the guideway 128 of the pedestal 130, the heel holder 26 being supported through said screw which may be initially adjusted in the depending plunger 126 of the platform 124 in accordance with the height of the heel to be attached to the shoe.

The shoe support 20 which is substantially identical with the shoe support disclosed in United States Letters Patent No. 2,259,568, granted October 21, 1941, on an application filed in the name of Thomas A. Kestell, et al. comprises a jack post 146 (Fig. 1) which is pivoted upon a slide (not shown) movable forward and rearward in a guideway (not shown) at the lower end of a pressure plunger (not shown). The shoe 21 mounted upon the last 23 is placed right side up and toe end forward on the jack post 146 and is slid rearward into a U-shaped band 148 which enters the rand crease of the shoe and cooperates with other mechanism (not shown) to position and clamp said shoe in the support 20 as shown and described in said patent.

After the machine has completed the first of its two cycles with the shoe 21, into the heel seat 56 of which the nails 50 have been driven, in its position shown in Fig. 1 above the nailing die 49, the operator places the pricked heel 40 on the heel holder 26 then in its dash line position shown in Fig. 1 and rotates the hand crank 70, the operation of which is described in detail in said Patent 2,391,543 to cause the carriage 34 to be moved to the right against the stop face 68 in the main frame to a position in which the heel holder 26 is in its operative position beneath the shoe support 20. When the heel 40 is thus positioned the awl holes 54 in the attaching face of the heel are positioned directly below the nails 50 respectively, which extend from the heel seat

56 of the shoe. As above explained, when the heel is engaged by the fingers 44, 46 during upward movement of the heel with the shoe to which it has been attached as a result of the "spanking on" operation, the heel is in danger of becoming marked. Accordingly, it is desirable that the fingers 44, 46 be spread apart before the heel, after its attachment to the shoe, shall be drawn out of the fingers. With the above consideration in view there is slidably in a horizontal bore 150 (Figs. 2 and 4) of the table 72 the above-mentioned rod 152, the head of which is constructed and arranged to be engaged by the stop screw 96. The stop screw is threaded into a depending lug (Fig. 2) of the lever 104, said rod, through mechanism which will be described presently, being slid forward to operate the lever 104 and accordingly to cause the fingers 44, 46 to be opened in response to mechanism actuated by upward movement of the plunger 64.

The depending portion 134 of the table 72 has secured to it by one or more screws 158 (Fig. 4) (only one shown) a bracket 160 (Figs. 4 and 5) having a vertical slot 162 across which extends a pivot pin 164 secured to the bracket. Secured by screws 166 to the platform 124 is a bracket 168 provided with a vertical bore 170 for receiving a shank portion of a slide 172, an upper plate portion of which is constantly urged toward a face 174 of the bracket 168 by a spring 176. Journaled on the pin 164 is a bell crank lever 178, an upper arm of which is positioned adjacent to the rear end of the rod 152 and a lower arm of which engages the plate portion of the slide 172.

As best shown in Fig. 6 the depending plunger 126 of the platform 124 has a rear flat face 180 and the pedestal 130 is slotted for the reception of a guide 182 which is secured to the pedestal by screws 184, said guide comprising a plate 186 which covers the upper rear portion of the guide and is secured to the main portion of the guide by the screws 184. Mounted for vertical reciprocation in a guideway 188 of the guide 182 and in a bore 190 of the pedestal 130 is a cam slide 192 which is constantly urged downward by a spring 194 interposed between the upper end of the cam slide 192 and a horizontally disposed lug 196 of the plate 186. Mounted in a slot 198 of the slide 192 for pivotal movement upon a pin 200 carried by said slide is a tumbler 202 which, in effect, constitutes part of an inclined surface 204 of said cam slide.

Mounted upon a pivot pin 205 carried by a boss 206 of the pedestal 130 is a multiarm lever 208 comprising an arm 210 carrying a roll 212 which is constantly forced against the face 204 of the cam slide 192 by a spring 214, forward and rear ends of which are attached to studs secured to the pedestal and to the lever 208 respectively. The lever 208 also comprises an arm 216 which extends upward to a position in front of an arm 218 of a lever 220 which is pivotally mounted upon a pin 222 carried by the bracket 168 and into which is threaded a screw 224 in engagement with the slide 172, clockwise rotation of the lever 220 under the action of the spring 176 being limited by the engagement of the arm 218 of the lever with a stop plate 226 secured by screws 228 to the bracket 168.

During a second cycle of operation of the machine the shoe support 20 then in the position shown in full lines (Fig. 1) is lowered forcing the nails 50 in the heel seat 56 of the shoe into the awl holes 54 of the heel and moving said

heel seat into engagement with the attaching face 58 of the heel. As disclosed in said Letters Patent 2,391,543, as the shoe support 20 is lowered a toggle (not shown) is straightened causing a stud 230 secured to the plunger 64 which is operatively connected to said toggle, to be raised prior to the engagement of a face 232 of the plunger with the nut 142 and accordingly before forcing the heel 40 with heavy pressure against the heel seat 56 of the shoe.

Upward movement of the stud 230 together with the plunger 64 raises the cam slide 192 along the guideway 188 causing the multiarm lever 210 to swing clockwise as viewed in Fig. 4 thereby effecting counterclockwise movement of the lever 220 and upward movement of the slide 172 against the action of the spring 176. As the slide 172 is raised the bell crank lever 178 forces the rod 152 forward thereby swinging the lever 104 counterclockwise as viewed in Fig. 2 against the action of the springs 92, 94 causing opposite pairs of fingers 44, 46 to swing outward away from the heel, the pin 116 of the hand knob 110 operated by the spring 112 moving in front of the shoulder 122 of the table 72 as the lever 104 is swung counterclockwise, to hold said fingers away from the heel.

After the application of final clamping pressure between the shoe 21 and the heel 40, the shoe support 20 and the heel support 26 are raised and lowered respectively, the shoe to which the heel has been attached then being removed from the shoe support.

During upward movement of the cam slide 192 the tumbler 202 is prevented from rotating clockwise as viewed in Fig. 4 by a face 234 of said slide, said tumbler when the slide is fully raised being elevated above the roll 212. When the cam slide 192 is lowered by the action of the spring 194 the tumbler 202 rotates idly counterclockwise upon the pin 200, thus allowing the cam slide to be moved downward. When the tumbler 202 has moved to a position below the roll 212 it swings back to its original position shown in Fig. 4 upon the cam slide 192. If desirable the tumbler 202 may be discarded and the cam face 204 of the cam slide 192 built out to replace said tumbler, such a construction being satisfactory but necessitating a return spring stronger than the illustrated spring 194.

When the shoe to which the heel has been attached has been removed from the shoe support 20 the operator by the use of the hand crank 70 moves the carriage 34 to a position in which the heel holder 26 secured to the carriage is in its dash line position illustrated in Fig. 1 and in which the nail driving mechanism 28 is arranged below the shoe support 20 preparatory to placing another heel in the heel holder and driving another group of nails 50 into the heel seat 56 of the next shoe to which a heel is to be attached.

Although the invention has been described with reference to the machine disclosed in said Patent 2,391,543 it will be understood that the nails 50 may be driven into the heel seat 56 of the shoe by the use of a separate machine, in which event the heel holder 26 will be permanently positioned below the shoe support 20. Moreover the invention has general utility in various types of machines for attaching heels to shoes such, for example, as machines in which heels are attached by nails driven from the inside of the shoe or in which heels are adhesively attached to the shoe.

Having thus described my invention, what I claim as new and desire to secure by Letters Patent of the United States is:

1. In a heel attaching machine, a heel holder, means comprising clamps for positioning a heel upon and securing it to the holder, a support for a shoe, said holder and support being relatively movable to cause the heel upon the holder and the heel seat of the shoe upon the support to be forced against each other, and means movable in timed relation to relative movement of the support and the holder for moving the clamps away from the heel before final heel attaching pressure is applied between the heel and the heel seat of the shoe.

2. In a heel attaching machine, a heel holder, means comprising clamps for positioning a heel and securing it to the holder, a support for a shoe, said holder and support being movable toward each other to cause the heel upon said holder and the heel seat of the shoe upon the support to be forced with heel attaching pressure against each other, and means movable in timed relation to movement of the holder toward the shoe support for moving the clamps away from the heel before final heel attaching pressure is applied between the heel and the heel seat of the shoe.

3. In a heel attaching machine, a holder for a heel, a breast gage carried by the holder, clamps mounted for engagement with opposite sides of the heel to center said heel upon and to retain it in the holder, a holder for a shoe, said shoe holder and heel holder being mounted for relative approaching movement to force together with heel attaching pressure the heel and the heel seat of the shoe, said heel and shoe holders being mounted for relative movement of separation preparatory to removing the shoe and its attached heel from the machine, and means movable in timed relation to relative approaching movement of the heel holder and the shoe holder for moving said clamps out of engagement with the heel before final heel attaching pressure is applied between the heel and the heel seat of the shoe.

4. In a heel attaching machine, a holder for a heel, means comprising fingers movable to closed positions for clamping the heel in a predetermined position in the holder, resilient means for constantly urging said fingers toward

their closed positions, a holder for a shoe, said heel and shoe holders being movable toward each other to force against each other with heel attaching pressure the attaching face of the heel and the heel seat of the shoe, means movable in timed relation to movement of one of the holders toward the other for moving against the action of said resilient means said fingers to open positions spaced from the heel before final heel attaching pressure is applied between the heel and the heel seat of the shoe, and means for automatically locking the fingers in their open positions, said last-named means being manually releasable to cause the fingers to be moved by said resilient means to their closed positions.

5. In a heel attaching machine, a support for a shoe, a pedestal constructed and arranged to be moved to and from an operative position adjacent to the support, a platform, a table for supporting a heel to be attached to the shoe, said table being removably supported upon the platform, means comprising fingers movable from open positions away from the heel upon the table to closed positions in which they locate said heel on and secure it to the table, said support being movable toward the table to force a fitted heel seat of the shoe on said support with initial pressure against the attaching face of the heel upon the table, said platform being movable in said pedestal to force the attaching face of the heel mounted upon the table with secondary pressure against the heel seat of the shoe, and mechanism, portions of which are independently movable with the platform and the table respectively, said mechanism being operative in timed relation with the platform to move the fingers prior to application of secondary pressure of the heel against the heel seat of the shoe to their open positions away from the heel and to retain said fingers in said open positions.

THOMAS BAGGOTT CLARKE.
